(57) **CLAIM**

The ornamental design for a coaming ladder, as shown and described.

DESCRIPTION

FIG. 1 is a perspective view of a coaming ladder, showing the new design;

FIG. 2 is a perspective view of the coaming ladder of FIG. 1, also showing non-claimed environment in broken lines;

FIG. 3 is a right side view of the coaming ladder of FIG. 1, also showing non-claimed environment in broken lines;

FIG. 4 is a left side view of the coaming ladder of FIG. 1, also showing non-claimed environment in broken lines;

FIG. 5 is a top view of the coaming ladder of FIG. 1, also showing non-claimed environment in broken lines;

FIG. 6 is a bottom view of the coaming ladder of FIG. 1;

FIG. 7 is a front view of the coaming ladder of FIG. 1, also showing non-claimed environment in broken lines;

FIG. 8 is a rear view of the coaming ladder of FIG. 1;

FIG. 9 is a rear view of the coaming ladder of FIG. 1, also showing non-claimed environment in broken lines; and,

FIG. 10 is a perspective view of an upper portion of the coaming ladder of FIG. 1, also showing non-claimed environment.

The broken lines showing a portion of a barge on which the coaming ladder is used represent environmental structure and form no part of the claimed design.
